Primary Examiner — John M Otte(74) *Attorney, Agent, or Firm* — Edell, Shapiro & Finn, LLC**CLAIM**

The ornamental design for a display screen or portion thereof with graphical user interface, as shown and described.

DESCRIPTION

The FIGURE is a front view of a display screen or portion thereof with graphical user interface showing our new design.

The long dash, short dash broken lines in the FIGURE depict a display screen or portion thereof and form no part of the claimed design. The remaining short dash, short dash broken lines depict portions of a graphical user interface and form no part of the claimed design.
